United States Patent Office.

JOHN B. ROSE AND JEROM B. BROWN, OF NEW LONDON, WISCONSIN.

Letters Patent No. 95,143, dated September 21, 1869.

IMPROVED UPSET, PUNCH, AND SHEARS.

The Schedule referred to in these Letters Patent and making part of the same.

To all whom it may concern:

Be it known that we, JOHN B. ROSE and JEROM B. BROWN, of New London, in the county of Waupaca, and State of Wisconsin, have invented certain new and useful Improvements in Upset for Punch and Shears; and we do hereby declare that the following is a full, clear, and exact description thereof, reference being had to the accompanying drawings, and to the letters of reference marked thereon, which form a part of this specification, and in which—

Figure 1 represents an end view, and

Figure 2, a plan view of our upset, punch, and shears.

Similar letters of reference indicate like parts in both figures.

Our invention relates to improvements in upset for punch and shears; and to this end,

It consists in the employment of an eccentric lever, in combination with a curve-bed and other devices for bending the tire.

It further consists in the employment of a punch and shears, operated by means of eccentric lever and other devices, substantially in the manner and for the purpose hereinafter described.

To enable others skilled in the art to which our invention appertains, to make and use the same, we will now describe its construction and operation.

In the accompanying drawings—

A A' represent two parallel bars, or beams, made as seen in fig. 2, and secured together, at suitable distance apart, by means of the cross-piece, or bar B. It will be observed that the cross-bar B is formed with a shoulder, C, and the end of the shoulder secured to the beam A, thereby more completely securing the beams A A'.

On the upper surface of the cross-bar, or brace B is secured the projection a, made with a curved end, and formed with a groove, which extends the whole height of the projection, and connects with the mortise formed in the cross-bar B. In this groove and mortise is inserted key b.

c represents a curved piece, or projection, attached to the cross-bar B and shoulder C, as seen in fig. 2.

d is an adjustable plate, shaped like piece c, and sliding upon the shoulder C. The slide d is formed with a neck and mortise, through which passes a screw, d', by which the slide is held in position.

At the rear end of the slide d, in the shoulder C, is

formed a mortise, into which is inserted a key, e, so that by driving the key in the mortise, the sliding plate d can be placed at any desired distance from the curved piece, or projection c.

On the upper surface of the shoulder C, near its end, is secured the punch f, which is inserted in a bed formed by the pieces g g'.

E represents a projection, formed on the inner edge of the cross-piece B, directly opposite the punch, and is formed with a recess, i, to receive the tire to be punched, said tire being retained in place by means of a key, h.

The other end of the punch is formed with an arm, which passes down into a recess, j, formed on the inner side of the lever F, by which arrangement, when the lever is operated, the punch is made to have a horizontal motion.

The lever F is pivoted at one end to the projection G, formed on the upper surface of the beam A, and is formed on its upper side with the recess k, the ends of the said recess being made curved, as seen in fig. 2.

l represents a key, inserted in the recess k, and entering a mortise formed in the lever F, by which arrangement the tire is held in said recess.

H represents a hollow projection, (made as seen in fig. 2,) formed on the outer end of beam A'. In this projection is pivoted the eccentric lever H', connected to the lever F by the strap p.

N represents the shears, pivoted to the projection g, on the beam A'. These shears are used to cut the tire.

Having thus described my invention, what I claim as new, and desire to secure by Letters Patent, is—

The improved machine herein described, consisting of beams A A', cross-brace B, projections a c g, adjustable plate d, keys b h e, levers T and H', and shears N, all arranged and operating substantially in the manner and for the purpose described.

In testimony that we claim the foregoing as our own, we affix our signature, in presence of two witnesses.

JOHN B. ROSE.
JEROM B. BROWN.
